UNITED STATES PATENT OFFICE.

JOHN J. HOUTZ AND WILLIAM L. HARRIS, OF MERWIN, MISSOURI.

SILO-ROOF.

1,153,082.

Specification of Letters Patent.

Patented Sept. 7, 1915.

Application filed November 24, 1914. Serial No. 873,823.

To all whom it may concern:

Be it known that we, JOHN J. HOUTZ and WILLIAM L. HARRIS, citizens of the United States, residing at Merwin, in the county of Bates and State of Missouri, have invented new and useful Improvements in Silo-Roofs, of which the following is a specification.

This invention relates to improvements in roofs for silos and has particular application to a sectional roof.

In carrying out the present invention, it is our purpose to provide a roof of the class described which will embody in its construction, among other features, a number of sections capable of relative swinging movement to open and closed positions so that the upper end of the silo may be opened when it is desired to fill the same and subsequently closed to keep out rainwater, dirt and the like.

It is also our purpose to provide a silo-roof which will embrace the desired features of simplicity, efficiency and durability, which may be applied to the silo without altering the construction thereof and which, when applied, may be operated with ease and convenience.

With the above and other objects in view, the invention consists in the construction, combination and arrangement of parts hereinafter set forth in and falling within the scope of the claims.

In the accompanying drawings; Figure 1 is a fragmentary side elevation of a silo equipped with a roof constructed in accordance with the present invention, the sections of the roof being shown in closed position. Fig. 2 is a view similar to Fig. 1 showing the sections of the roof in open position. Fig. 3 is a vertical sectional view through the silo and roof thereon. Fig. 4 is a similar view taken at right angles to Fig. 3.

Referring now to the drawings in detail, 45 1 designates the upper portion of a silo of some suitable construction.

Secured to the side wall of the silo adjacent to the upper end thereof at diametrically opposite points are base plates 2 50 equipped with outwardly extending axially alining trunnions 8.

4 designates the roof of the silo comprising a hemispherical body formed of two sections 5 and 6.

The open end of the body is reinforced by

means of an angle iron 7 extending around the inner circumference thereof and having one flange secured to the inner wall of the body and the remaining flange disposed at the lower edge of the first flange and extending into the body in a substantially horizontal plane. This angle iron is, of course, split at the adjoining ends of the sections of the roof and the particular end of the section 6 overlaps the adjacent end of the section 5 as clearly illustrated in the drawings, while secured to the inner end of the section 6 and extending around such end from one extremity to the other is an angle iron 8 having one flange bolted or otherwise fastened to the outer surface of the section 6 at the inner edge thereof and the remaining flange disposed contiguous to the edge and extending outwardly therefrom, while secured to the section 5 beyond the adjacent edge thereof is an angle iron 9 having one flange bolted to the particular section of the roof and extending from one extremity to the other and the remaining flange designed to abut the outwardly extending flange of the angle iron 8 on the section 6 when the sections 5 and 6 of the roof are assembled in roof formation. The overlapping edges of the sections 5 and 6 at the ends thereof are provided with horizontally alining boxings 10 through which are passed the trunnions 3 whereby the roof 4 is supported upon the silo and the sections 5 and 6 enabled to swing relatively to each other so that the adjacent ends thereof may be separated when it is desired to fill the silo.

The outer ends of the trunnions 3 are braced by suitable braces 11, while encircling the trunnions are coiled expansion springs 12, 12 respectively disposed between the wall of the silo and the boxings carried by the edge of the section 5 of the roof, such springs acting to hold the roof against movement relatively to the silo along the trunnions and enabling the silo to contract and expand without affecting the roof. Braces 13 are also employed and secured to the wall of the silo immediately below the open end of the roof and are adapted to engage the bottom edge of the roof to maintain the latter stable.

In the present instance, each brace 13 is formed of a horizontal limb and a depending vertical limb 20 formed with a slot 21, and a support 22 secured to the adjacent portion of the wall of the silo. Secured to one side

wall of the support 22 is a horizontal pin 23 passed through the slot 21 in the depending vertical limb of the bracket. When the brackets are active the upper ends of the slot 21 engage the pins 23 while the inner edges of the vertical limbs of the brackets engage the adjacent portions of the wall of the silo, thereby preventing swinging of the brackets.

10 A rope 14 or other flexible element has one end fastened to the inner surface of the section 5 adjacent to the inner edge of such section by means of a ring 15 and the opposite end trained over a guide sheave 16 secured to the inner surface of the section 6 adjacent to the inner edge thereof and thence downwardly alongside of the silo.

In practice, the sections 5 and 6 of the roof are normally held in closed position 20 and when it is desired to separate the meeting ends of the sections so that the silo may be filled, the cord 14 is released and the sections 5 and 6 gravitate to open position and swing about the trunnions 3, the braces 13 having been previously disengaged from the lower edge of the roof.

In order to disengage the braces 13 from the lower edge of the roof of the silo, the lower ends of the depending vertical limbs 30 of such braces are engaged by a pole and moved upwardly and this upward movement of the braces is permitted by the pin and slot connection between the vertical limbs thereof and the supports for the braces, the pin and slot connections being clearly illustrated in Fig. 3 of the drawings. When the vertical limbs of the braces have reached their limit of upward movement the outer extremities of the horizontal limbs 40 thereof drop downwardly owing to the vertical limbs being relieved of the restraining influence of the side wall of the silo. Thus, it will be seen that the braces may be quickly

and conveniently operated to relieve the sections of the roof.

45

We claim:

1. The combination with a silo, of trunnions secured to the silo adjacent to the upper end thereof and projecting outwardly therefrom at diametrically opposite points, 50 and a roof comprising a hemispherical body formed of two sections, boxings carried by the opposite ends of the inner edges of said sections journaled upon said trunnions whereby the section of the roof may be 55 swung to open and closed positions, and springs encircling said trunnions and acting to hold the sections of the roof normally against lateral movement relatively to the silo.

60

2. The combination with a silo, of trunnions secured to the silo adjacent to the upper ends thereof and projecting outwardly therefrom at diametrically opposite points, a roof comprising a hemispherical body 65 formed of two sections, boxings carried by the opposite ends of the inner edges of said sections journaled upon said trunnions whereby the sections of the roof may swing to open and closed positions, a guide sheave 70 carried by the inner surface of one of said sections, a flexible element trained over said sheave and having one end connected to the inner surface of the other section and the remaining end portion extending downwardly along the silo whereby the sections of the roof may be swung into roof formation.

75

In testimony whereof we affix our signatures in presence of two witnesses.

JOHN J. HOUTZ.
WILLIAM L. HARRIS.
